US00D916104S

(12) **United States Design Patent** (10) Patent No.: **US D916,104 S**
(45) Date of Patent: **** Apr. 13, 2021**

(54)	DISPLAY PANEL OF A PROGRAMMED COMPUTER SYSTEM WITH A GRAPHICAL USER INTERFACE	4,276,561 A	6/1981	Friedman
		4,449,941 A	5/1984	McGuire et al.
		D298,144 S	10/1988	Wells-Papanek et al.
		D309,718 S	8/1990	Fotovat
		5,030,100 A	7/1991	Hilderman
		5,057,024 A	10/1991	Sprott et al.
		D331,575 S	12/1992	Pike
		5,226,725 A	7/1993	Trusiani
		5,664,126 A	9/1997	Hirakawa et al.
(71)	Applicant: Facebook, Inc. , Menlo Park, CA (US)	D388,777 S	1/1998	Newton et al.
(72)	Inventors: Matthew Cahill , San Francisco, CA (US); Mark E. Zuckerberg , Palo Alto, CA (US)	D389,471 S	1/1998	Newton et al.
		D393,634 S	4/1998	Stuckey
		5,745,713 A	4/1998	Ferguson et al.
		D395,296 S	6/1998	Kaye et al.
(73)	Assignee: Facebook, Inc. , Menlo Park, CA (US)	D397,999 S	9/1998	Kovanen et al.
(***)	Term: 15 Years	D409,662 S	5/1999	Ho
(21)	Appl. No.: 29/599,076	5,931,677 A	8/1999	Rifat et al.
(22)	Filed: Mar. 30, 2017	5,945,985 A	8/1999	Babin et al.
	Related U.S. Application Data	D416,044 S	11/1999	Martin
(63)	Continuation of application No. 29/540,488, filed on Sep. 24, 2015, now Pat. No. Des. 787,528, which is a continuation of application No. 29/511,466, filed on Dec. 10, 2014, now Pat. No. Des. 742,415, which is a continuation of application No. 29/456,485, filed on May 31, 2013, now Pat. No. Des. 723,583, which is a continuation of application No. 29/409,550, filed on Dec. 23, 2011, now Pat. No. Des. 685,818, which is a continuation of application No. 29/355,130, filed on Feb. 3, 2010, now Pat. No. Des. 653,671.	D417,208 S	11/1999	Steele
(51)	LOC (13) Cl. 14-04	D417,466 S	12/1999	Ho
(52)	U.S. Cl.	D419,456 S	1/2000	Ho
	USPC D14/486	D424,545 S	5/2000	Moody
(58)	Field of Classification Search	D426,206 S	6/2000	Richter

CLAIM

We claim the ornamental design for a display panel of a programmed computer system with a graphical user interface, as shown and described.

DESCRIPTION

FIG. 1 is a front view of a display panel of a programmed computer system with a graphical user interface; and, FIG. 2 is a front view of a portion thereof, on an enlarged scale, for ease of illustration.

The broken line showing a display panel forms no part of the claimed design. The broken lines showing portions of the graphical user interface form no part of the claimed design.

1 Claim, 2 Drawing Sheets

FIG. 1

FIG. 2
